Patented Feb. 16, 1926.

UNITED STATES PATENT OFFICE.

JOSEPH LACHAINE, OF LOWELL, MASSACHUSETTS.

MULTIPLE METAL CABINET.

Application filed June 29, 1925. Serial No. 40,443.

To all whom it may concern:

Be it known that I, JOSEPH LACHAINE, a citizen of Canada, and a resident of Lowell, in the county of Middlesex and State of Massachusetts, have invented certain new and useful Improvements in Multiple Metal Cabinets, of which the following is a specification.

This invention relates to improvements in cabinets, particularly to such as are made of sheet metal, and which are light, strong, fire-proof and sanitary.

The main object is to provide a group or series of independent cabinets, so co-related that two or more of their partition walls also act as partition walls for adjacent cabinets, each cabinet being however distinct and separately usable.

A further object is to so construct the walls of the cabinet as to interengage at their corners in a firm and substantial manner, but permitting their disassociation for transportation or storage in compact form.

Still further objects are to provide shelves, floors and covers within the cabinets, which like the vertical walls, are of knock-down construction.

These and other objects are attained by the novel construction, combination and arrangement of parts hereinafter described and shown in the accompanying drawings, forming a material part of this disclosure, and in which:—

Figure 1 is a perspective view showing a group of cabinets made in accordance with the invention, parts being omitted in order to disclose the construction.

Figure 2 is a fragmentary top view at one of the inner joints.

Figure 3 is a top plan view of one of the inner partitions.

Figure 4 is a similar view of one of the corner partitions.

Figure 5 is a side elevational view of the parts shown in Figure 2.

Figure 6 is a similar side view of the element shown in Figure 3.

Figure 7 is a like side view of the part shown in Figure 4.

Figure 8 is a plan view of the central top or cover in detail.

Figure 9 is a similar plan view of one of the side cover plates.

Figure 10 is a plan view of one of the shelves.

Referring to the drawings in detail, the

numeral 15 designates the front element of the left hand cabinet, 16 the front of the center compartment, and 17 the front element at the right hand end. 60

Each of these elements, and those corresponding to them on the opposite side of the group, are rectangular in shape and contain openings 15', 16' and 17' through which the interior of the compartments are accessible, these openings being provided with doors (not shown) if desired. 65

The side or end plates 20 and 21 are arranged in pairs and held together along their adjacent lateral edges by partition plates 22 in the following manner. 70

The outer edges of the plate 22 are sheared, as at 23 and 23', the material at the margins being bent oppositely, above and below the cuts 23 and 23', and then turned re-entrantly in, forming spaced hooks 26 and 26', and 28 and 28'. 75

In a closely similar manner the adjacent marginal edges of the plates 20 and 21 are bent at right angles and then turned re-entrantly, forming hooks 30 and 32, which when entered in the hooks 26 and 28 by sliding the plates lengthwise, relatively to the other, become interlocked and firmly held in engagement. 80

The outer marginal edges are extended straight out and formed into continuous hooks 31 and 33 engaging in a similar manner with the angularly turned and folded edges 34 and 36 of the front plates 15, the rear edges of which are folded and turned in a like manner, forming hooks 35 and 37 engaging the marginal hooks of the partition plates 38 and 40, the structure being continued indefinitely in the same general 85 manner. 90

At points near the bottom of the several side and intermediate vertical partitions or walls, 20—40 etc., the plates are formed with one or more upstanding projections 42 and 43, upon which rest bottom plates or floor elements 44. 100

Also at points near the upper ends of the same walls the material is sheared and bent at right angles inward, forming supports 45 for shelves 46, these shelf plates being re-enforced along their edges by beadings 47, as best shown in Figure 10. 105

The extreme upper ends of the front walls 15, 16 and 17 are turned at right angles inwardly forming supports 48, while the side walls 20 and 21 are turned in a like 110

manner forming projections 49, having interposed centrally in their length integrally formed spring securing clips 50.

The partition plates 22 at the back of each compartment, and the side partitions 40 have their upper ends sheared and bent in opposite directions, forming supports 52 and 54 at the backs, the supports 53 and 55 extending from the side partitions into the adjacent compartments.

Resting over the several supports at the ends of the structure, after the vertical walls and partitions have been assembled are cover or roof plates 58 having downturned rear and end edges, respectively 56 and 60, the inner edges being formed with angular projections 61 and suited to closely engage the walls of the compartment.

The center cover or roof plates 64 have similar end edges 65 and their side edges are bent to fit closely adjacent to the projections 61, presenting a tight cover over the entire structure, preventing the entrance of dust and the like, after the clips 50 have been pressed forward over the end cover plates.

While Figures 1, 2 and 3 and 4 show a specific manner of interlocking the adjacent edges of the plates, it will be understood that any other equivalent locking means may be employed without departing from the spirit and scope of the appended claims.

From the foregoing it will be seen that a novel type of grouped cabinets has been disclosed which effectually fulfills the stated purposes.

Having thus described my invention, what I claim as new and desire to secure by Letters Patent, is:—

1. A multiple cabinet having compartments arranged in opposed adjacent pairs, each compartment being rectangular and comprised of vertical plates so arranged that the inner plates act as walls for adjacent compartments, opposed seamed longitudinal edges formed on each plate, the seams of one plate being slidably engageable with the seams of juxtaposed plate, and means formed with the edges of the inner plates engageable with each pair of adjacent outer plates by which they are interlocked together.

2. A multiple cabinet having compart-

ments arranged in opposed adjacent pairs, having openings in their front walls, shelves in each compartment accessible through the mentioned openings, supports for said shelves formed integrally with the inner walls of each compartment, angular turned supports at the tops of each wall extending into each compartment, a cover plate for each pair of compartments, means formed with the edges of said cover plates engageable over said walls, and clips formed with the upper ends of each outer side wall engageable over the cover plates at the ends of the structure.

3. A metal cabinet comprising a front plate having an opening, a side plate, a back plate and inner side plate, said back plate forming the rear wall of a cabinet opposed to the first and said inner side plate acting as a partition for an adjoining cabinet, sheared supports formed with said side and back plates, a shelf adapted to rest upon said supports, means integrally formed at the corners of the cabinet for holding the four walls in fixed relation, a cover extending beyond said cabinet and adapted to cover an adjoining cabinet, means formed with the edges of said cover for holding it in fixed relation, and clips formed with the outer side plate adapted to clamp said cover over the cabinets.

4. A multiple cabinet having a plurality of compartments each having side walls interengaged by uninterrupted seams at their edges, a base platform for each compartment, cover plates extending thereover and shelves arranged interiorally of each compartment, said shelves acting as spreaders for the walls.

5. A multiple compartmented cabinet comprising side walls, a base plate, a cover plate, said base plate being adapted to hold said walls in a spread condition, shelves interposed in the length of said walls, interengaging seams at the longitudinal edges of each of said compartments, other engaging means between said base and cover plate and said walls, and means for locking said cover plate when in an assembled position.

In testimony whereof I have signed my name to this specification.

JOSEPH LACHAINE.
